Des. 177,578
Patented May 1, 1956

177,578

SUCTION CLEANER SPRAYER ATTACHMENT

Eugene F. Martinec, East Cleveland, Ohio, assignor to
Health-Mor, Inc., Chicago, Ill., a corporation of Illinois

Application March 21, 1955, Serial No. 35,137

Term of patent 14 years

(Cl. D62—2)

Fig. 1

Fig. 2

Figs. 1 and 2 are diametrically opposed perspective views of a suction cleaner sprayer attachment showing my new design.

I claim:

The ornamental design for a suction cleaner sprayer attachment, substantially as shown.
